F. SHARP ET AL

TROLLEY HEAD FOR ELECTRIC TRAMCARS

Filed Aug. 4. 1921

FIG. 1.

FIG. 2.

FIG. 3.

INVENTORS,

FRED SHARP,
JOHN MARTIN,

By *Henry P. Bright*
Attns.

UNITED STATES PATENT OFFICE.

FRED SHARP AND JOHN MARTIN, OF BARROW-IN-FURNESS, ENGLAND.

TROLLEY HEAD FOR ELECTRIC TRAMCARS.

Application filed August 4, 1921. Serial No. 489,907.

(GRANTED UNDER THE PROVISIONS OF THE ACT OF MARCH 3, 1921, 41 STAT. L., 1313.)

To all whom it may concern:

Be it known that we, FRED SHARP and JOHN MARTIN, both subjects of the King of Great Britain, residing at Barrow-in-Furness, Lancashire, England, have invented certain new and useful Improvements in Connection with Trolley Heads for Electric Tramcars (for which application has been filed as follows: Great Britain, Nov. 3, 1919, 10 Patent No. 144,183), of which the following is a specification.

This invention relates to trolley heads for electric tram cars of the kind in which a shield is disposed upon each side of the 15 pulley so as to project above the same which shields are pivotally mounted upon the axis pin of the trolley pulley and held in normal vertical position by spring means in such a manner that such shields can turn 20 backwards against the spring pressure when encountering an obstacle. The object of these shields is to prevent the pulley from leaving the cable when meeting an obstacle such as the usual supporting frogs.

25 According to the present invention the shields are formed integral with each other and comprises a pair of upstanding or vertically disposed ears the upper extremities of which constitute the shields whilst the 30 lower extremities constitute the points of pivotal connection with the axis pin of the pulley. A channel shaped arm is formed integral with said ears and extends rearwardly therefrom and approximately at 35 right angles thereto for a convenient distance in which position it is normally maintained by a compression spring.

Upon meeting an obstruction the ears are 40 turned about their pivot the arm being similarly depressed against the action of the compression spring which operates to return the shields to their normal position when the obstruction is passed.

In order that the invention may be clearly 45 understood the same will now be described by aid of the accompanying drawings in which:—

Fig. 1 is a side elevation and Fig. 2 and 50 end elevation of the device constructed in accordance with the present invention.

Fig. 3 is a view illustrating the rope attachment for manipulating the trolley.

In the drawings *a* indicates the trolley head which is of the ordinary construction

and in which the device forming the subject 55 of this invention is fitted. The device consists of a channelled member *b* made of brass which is at one end pivotally mounted on the axle of the pulley wheel or sheave *c* and having its sides at that end projecting 60 upwardly see *d* Figs. 1 and 2 a suitable extent, with the outer surfaces of the projections *d* in frictional contact with the sides of the trolley head *a*.

A compression spring *e* arranged around 65 a bolt or pin *f* fixed at its lower end to a plate or bearer *g* fixed to a lug *h* on the trolley head has its upper end passed through a hole formed in the bottom of the channelled member *b*. The bolt or pin *f* is screw 70 threaded at its free end and a nut *i* screwed thereon to retain said pin or bolt in position in the hole in the channelled member *b*. The lower end of the spring *e* rests against the plate or bearer *g* while its upper end bears 75 against the under surface of the channel *b* and said spring *e* is placed under compression to the required extent to maintain the projections *d* of the channelled member *b* in contact normally with the cable. 80

When any obstruction on the cable is met with the projecting sides *d* of the channelled member *B* make contact therewith and consequently the member *b* turns upon its axis in the direction of the arrow shown in Fig. 85 1. This movement depresses the channel *b* and the spring *e* is compressed. The depression of the channel *B* permits of the trolley head passing the obstruction and when it has cleared this obstruction the 90 spring *e* expands and returns the member *b* to no normal position.

The rope hole is constituted by an eyebolt *j* on the lug *h* and to the eye *j'* of this bolt the end *k* of a pair of wires are attached, 95 the free ends *k'* being outstretched to form a triangle with a stiffening wire *l* as a base. At the free ends *k'* loops or rings *m* are fixed and to these rings *m* the operating lines *n* are connected (see Fig. 3). 100

We declare that what we claim is:—

In a trolley head, the combination of a forked frame, a journal pin connecting the arms of said frame, a trolley wheel journaled on said pin, rotatable shield members 105 also journaled on said pin between each arm of the frame and the adjacent side of the trolley wheel adapted in normal position

to project above the wheel to prevent lateral disengagement of a trolley wire therefrom, mutually connecting arms projecting from the shield, a bracket on said forked frame, a rod secured at one end to said bracket and at its other end being slideable through the mutual connection of said arms, a stop on the last mentioned end of said rod to limit rotative movement of said arms and 10 said shields in one direction, a compression spring surrounding said rod and bearing

at its ends against said bracket and said mutual connection, respectively, to hold said mutual connection against said stop whereby the shields are held in normal position and 15 permitted to yield in one direction.

FRED SHARP.
JOHN MARTIN.

Signed in the presence of—

ALFRED BARROW,
T. A. MORGAN.
